UNITED STATES PATENT OFFICE

99,944

DESIGN FOR A WASTE BASKET

Frederic A. Hougland, Chicago, Ill., assignor to General Bindery Company, Chicago, Ill.

Application March 27, 1936, Serial No. 61,808

Term of patent 3½ years

To all whom it may concern:

Be it known that I, Frederic A. Hougland, a citizen of the United States, residing at Chicago, in the county of Cook and State of Illinois, have invented a new, original, and ornamental Design for a Waste Basket, of which the following is a specification, reference being had to the accompanying drawing, forming part thereof in which Fig. 1 is a front elevational view of a waste basket showing my new design, Fig. 2 is a top plan view thereof on a reduced scale, and Fig. 3 is a side elevational view thereof on a reduced scale. The rear side of Fig. 1 is substantially the same in appearance as the side disclosed.

I claim:

The ornamental design for a waste basket, as shown and described.

In testimony whereof I affix my signature.

FREDERIC A. HOUGLAND.
